UNITED STATES PATENT OFFICE.

ALEXANDER B. ROE, OF ATHENS, OHIO.

BOOKBINDING MACHINE.

Application filed February 9, 1925. Serial No. 7,918.

This invention relates to book-binding machines, and has particular reference to a machine of this character for binding volumes of varying dimensions.

5 An object of the present invention is the provision of such a machine, having means for forming semi-flexible backs for volumes from a single strip of material.

10 A further object of the invention is the provision of mechanism, whereby a single piece of back material may be scored and formed into shape and size to fit a particular volume under construction.

15 Another object of the invention is the provision of a book-binding machine, having means for receiving a strip of back material, properly gaging it with reference to the matter to be bound, scoring said strip, shaping and retaining it in proper position upon 20 the matter to be bound, and drilling the complete volume preparatory to the insertion of binding elements.

25 Other important objects and advantages of the invention will be apparent during the course of the following description. In the accompanying drawings,

Fig. 1 is a perspective view of mechanism embodying the invention;

Fig. 2 is an end elevation thereof, with 30 parts in slightly different position;

Fig. 3 is a horizontal sectional view of the machine taken on line 3—3 of Fig. 2;

Fig. 4 is a central vertical sectional view through the machine;

35 Fig. 5 is an enlarged vertical sectional view through a pressure bar, scoring mechanism and associated elements, illustrating the initial binding operation;

Fig. 6 is a similar view, illustrating a volume in place preparatory to drilling, and with the back scored and shaped into place;

Fig. 7 is a longitudinal sectional view through a scoring mechanism embodied in the invention;

45 Fig. 8 is a vertical section through a drilling mechanism and latch means therefor; and,

Fig. 9 is a perspective view of a completely bound volume, illustrating the several 50 scores for forming, in effect, hinges for the back.

Referring to the drawings in detail, the numeral 10 designates base members or supports upon which the machine is mounted.

55 Rigidly secured to these base members 10, are a pair of vertically arranged parallel

guide rods 11, connected at their upper ends by a rod 12, bolted or otherwise attached thereto as shown. The base members 10 are arranged in parallel relation, and are rigidly braced with respect to each other by rods 13 and 14, also arranged parallel with respect to each other.

60 Mounted for vertical reciprocatory movement upon the guide rods 11, is a work supporting table or carriage, designated as a whole by the numeral 15. This carriage 15 comprises parallel bars 16 extending longitudinally of the machine, and apertured for the passage of the guide rods 11. The bars 70 65 16 extend in advance of the guide rods 11, and are connected at their forward ends by an angle bar 17. The carriage 15 further comprises a table 18, arranged rearwardly of the rods 11. An evener board 19 is adjustably mounted upon the table 18 and may be shifted laterally thereof to accommodate the work thereon, it being provided with a set screw 19'. The top member 18 may be bolted or otherwise attached to the bars 16, 80 as shown. A binding gage 20 is mounted upon the table 18 and is adapted to partake of vertical swinging movement upon a rod 21, which is in turn carried by a bracket 22 having upturned ends 23 forming bearings for said rod 21. This gage 20 normally lies flat upon the table top 18, and may be shifted longitudinally thereof upon the rod 21, and retained in any desired position by a locking ring 24 provided with a set screw 25. 85 90

The carriage 15 further comprises a pair of cylindrical vertical supporting rods 26, connected at their upper ends by a bar 27 having upturned ends 28. The rods 26 are positioned in advance of the guide rods 11, 95 and pass through the upper face of the angle bar 17. A leaf supporting plate 30 is hingedly connected to a plate 30', which is in turn bolted or otherwise attached to the upper face of the angle bar 17, as shown. 100 As clearly shown, the leaf supporting plate 30 projects beyond the forward edge of the angle bar 17, and its outer edge is formed with a plurality of regular shaped notches 31, which are equidistantly spaced, for a 105 purpose to be described.

The numeral 32 designates a vertically reciprocating pressure bar, for compressing and retaining the work to be bound upon the table 18. This pressure bar 32 comprises 110 an angle bar 33 arranged in parallel relation with the angle bar 17. The angle bar

33 has, bolted or otherwise secured thereto, plates 34 and 35 corresponding to the lower plates 30 and 30', the plate 35 being identical with the plate 30 as concerns the notches 36 therein, the notches 36 in plate 35 corresponding in size and number to the notches 31 in plate 30 and being arranged in alignment therewith. The plate 34 projects slightly beyond the front edge of the angle bar 33, and is beveled downwardly as illustrated at 37. This beveled plate 34 co-acts with a shaping bar 38 pivotally mounted as at 38' for horizontal swinging movement in a block 39, as clearly illustrated in Fig. 3. 10 The shaping bar 38 is L-shaped in cross section, and has its horizontal face 40 notched as at 40', such notches corresponding in size, shape and number with notches 31 and 36 in the plates 30 and 35 and registering therewith. The shaping bar 38 normally lies over and in parallel relation to the plates 30 and 35, and is held in this position by a latch screw 41. The means for elevating the pressure bar 32 comprises a pair of revolvable 20 screws 42 having screw-threaded engagement at their lower ends in stationary blocks 43 rigidly secured to the angle bar 33. The upper ends of the screws 42 are journaled in the cross bar 27 and carry beveled pinions 44, which in turn mesh with beveled pinions 45 fixed upon a horizontal shaft 46. The shaft 46 is journaled in the upturned ends 28 of connecting bar 27, and carries upon one end thereof outwardly of the framework 35 of the machine, a hand wheel 47, having a hand crank 48 whereby the shaft 46 and associated elements may be rotated. It is therefore obvious that rotation of the shaft 46 will result in the rotation of the screws 40 through the medium of the pinions 44 and 45, thus elevating or lowering the pressure bar 32, dependent upon the rotation of the hand wheel 47. Rigidly secured to the pressure bar 32 at a point beneath the block 45 39, and extending at a right angle with respect to such bar 32, is a cam plate 49, whose cam face 50 is adapted to engage with, and limit the forward swinging movement of, a scoring bar 79 to be hereinafter described. 50 The cam plate 49 partakes of vertical movement with the pressure bar 32, the bevel face of the said cam plate providing a stop or rest designed to engage the carriage carrying the scoring bar, thus determining the limit 55 of forward movement of the scoring bar 79. Means are provided to move the carriage 15 and associated elements downwardly upon the guide rods 11 comprising a pair of upper links 51 and 52, and a pair of lower links 60 53 and 54. These links are pivotally connected together as shown at 55 and 56. The links 51 and 52 are pivoted upon blocks 57, in turn rigidly attached to the rods 26. The links 53 and 54 have their lower ends pivotally connected with the base members 10 as

shown at 58. The upper ends of the links 51 and 52 are connected by means of a hand bar 59. Normally the carriage 15 is held against movement in the elevated position by reason of the links 51, 52, 53 and 54 lying in the forward past-center position, and coming to rest upon the bar 27. When it is desired to lower the carriage 15, as is necessary in the operation of drilling a volume, the operator grasps the hand bar 59 and brings it forward, thereby swinging the several links upon their pivots and causing them to move to a rearward past-center position, and a continued forward movement of the hand bar 59 will result in the lowering of the carriage 15, due to the leverage imparted to it by the connections of the links 55 and 56. Any sudden lowering of the carriage 15 is prevented and retarded by the application of retractile coil springs 60, connected at their lower ends to plates 61 affixed to the carriage 15, and at their upper ends to the connecting rod 12. The springs 60 also tend to elevate the carriage 15 to its normal position, upon the release of pressure on the hand bar 59. 75 80 85 90

The numeral 62 designates a drive shaft for a drill 70 employed in the binding operation. This shaft 62 is driven by any suitable means, such as an electric motor 63 mounted upon a suitable support carried by rods 64, in turn rigidly attached to the base member 10 as shown. As shown, the motor support may be adjustably mounted upon the rods 64. The numeral 65 designates a gear housing adapted to receive and house gears 66 and 67. The gear 66 is mounted upon the drive shaft 62, and may partake of sliding movement thereon. The gear 67 is affixed to a vertical shaft 68, carrying at its upper end outwardly of the top of the housing 65, a chuck 69 for receiving and holding a conventional twist drill 70. The housing 65 and associated elements are adapted to partake of reciprocatory movement upon the rods 13 and 14 and the drive shaft 62, and may be locked in any predetermined position by a latch element 71, having a pin 72 for engaging in any one of a series of depressions 73 formed in the rod 13. The latch 71 is pivotally mounted within the housing 65, as at 74, in such manner that its greatest weight is upon one side of the pivot 74, whereby such weight will always tend to engage the pin 72 within one of the depressions 73 when the drill 70 is in proper position for operation. It might be stated at this point that the positions of the depressions 73 are such, that when the housing 65 is locked in any one depression the drill 70 will lie centrally of a corresponding series of notches 31, 36 and 40, thus when the carriage 15 is lowered with a volume in place the drill 70 will pass through the notches and through the matter being bound. The drill 70 may be shifted 100 105 110 115 120 125 130

along the rods 13 and 14 to varying positions, in order to enable the drilling of a plurality of holes in the volume. Whenever it is desired to shift the drill 70, it is first necessary to elevate the carriage 15.

Means have been provided for scoring the material designed to form the back and covers for the volume, which material is comprised of a single strip. The scoring mechanism is indicated as a whole by the numeral 75, and comprises vertically swinging support arms 76 and 77, pivotally supported at their lower ends upon the rod 13, but contacting with the base members 10 to prevent any longitudinal movement on the rod 13. Rigidly attached to the arms 76 and 77 adjacent their upper ends is a horizontal die bar 78, arranged in parallelism with the angle bar 17, and having its top edge lying in approximately the same horizontal plane with the top of the table 18. A co-acting die bar 79 is arranged above, and in parallel spaced relation with, the bar 78, and coacts therewith for scoring the back material therebetween. The die bar 79 is hingedly connected, as at 80, to side plates 80 carried by the arm 76, whereby the bar 79 may be swung in a vertical plane to permit of the insertion of material to be scored. A handle 81 is formed upon the bar 79 to facilitate the operation thereof. As clearly shown in Figs. 5 and 6, the die bar 78 is provided with channels 82 adjacent its outer edges and in its upper face. The formation 35 of these channels 82 leaves a central portion in the form of a rib 83, which extends for the entire length of the bar 78. It will be observed that the bar 79 is provided upon its lower contacting face with a channel 84, also extending for the entire length of the bar 79. The formation of this channel 84 provides a pair of ribs 85, which in their normal position lie within the channels 82 but spaced from the sides and bottom thereof, at which time the rib 83 will lie within the channel 84 a corresponding depth, the channels in both bars being of the same depth. As illustrated in Fig. 7, the lower bar 78 is provided with an upstanding lug 86, formed upon the rib 83. The purpose of this lug 86 is to properly space the bars 78 and 79, in order to effect the proper scoring of the blanks and to avoid cutting the material being scored. This spacing is the same throughout the entire length of the bars, as shown in Fig. 7, the upper bar 79 having its lower face slightly rounded, as at 87, to permit of its being swung upwardly without binding. The arm 77 is provided with a pair of guide plates, bolted or otherwise secured to its edges upon opposite sides of the bars, as shown at 88, and these plates 88 project above the top of the upper bar 79 and diverge slightly, to facilitate the entry of the bar 79 therebetween. The plates

88 are wider than the thickness of the arm 77, and project slightly therebeyond. A laterally swinging latch member 89 is pivoted at 90 to the carriage 15, and is provided with a pair of notches 91 adapted to engage 70 over the edge of the plates 88 to positively hold the scoring mechanism 75 in a predetermined position during the initial binding operation. The scoring is accomplished by raising the bar 79, placing the material 75 to be scored between said bar 79 and the bar 78, and then bringing the bar 79 down with sufficient pressure to force the material into the several channels, whereby said material will assume a shape as illustrated in Fig. 6. 80

If so desired, a conventional form of trimming knife may be embodied in this machine, to enable an operator to carry out upon a single machine all the steps of binding. This trimming mechanism embodies 85 the usual gaging or trimming board 92, having a metallic stationary knife 93 affixed thereto. This knife is adapted to co-act with a vertically swinging knife 94, pivoted in a fixed bracket or bearing 95 carried by 90 the board 92. The bracket 95 is provided with a cam face adapted to be engaged by a lug 96 carried by the head of the knife 94, and this lug 96 is held in engagement 95 with the cam face during the travel of the knife 94, by a spring 97 surrounding the pivot pin of the knife 94. In this manner the swinging knife 94 is always retained in proper cutting relation with the fixed knife 93. An operating handle 98 is formed upon 100 the swinging knife 94 to facilitate the operation thereof. As illustrated, the board 92 may be supported upon a pair of rods 99, affixed to the base 10 by means of blocks 100 having suitable set screws 100'. 105

Means are employed to counterbalance the swinging movement of the scoring mechanism 75 toward and away from the binding table 15, comprising a weight 101 affixed by a set screw 101' to an offset lever 102. This lever 102 is in turn pivotally attached to the face of the arm 77, as shown at 103, and in such position, relative to the lower ends of the plates 88, that when the scoring mechanism 75 is swung to the position shown in Fig. 1, downward-swinging movement of the lever 102 and weight 101 will be limited by the abutment of the lever 102 against the lower ends of the plates 88. When the mechanism is in this position, the weight of the scoring mechanism 75 will overbalance that of the weight 101, and will remain in this position until the scoring mechanism 75 is elevated sufficiently by the operator to enable the weight 101 to overbalance the weight of the scoring mechanism 75. When the scoring mechanism is swung outwardly, the movement is limited by the abutment of the weight 101 against 115 the head of the pivot 56. 120

Assuming that the parts are in the position illustrated in Fig. 1, the operation of the machine is as follows:

The hand wheel 47 is rotated to cause the pressure bar 32 to be elevated. A sheet of paper the size of that to be bound is placed upon the table 18, its forward edge lying exactly even with the outer edge of the plate 30. This operation is to enable the operator to properly gage the scoring of the back material. The gaging plate 20 is then raised, and moved over the sheet of paper so that its rear edge will be even with the rear edge of the paper, as shown in Fig. 5. The gage 20 is then set in this position by the locking collar 24, and we are now ready to make the first scoring of the back.

The scoring mechanism 75 is then swung upwardly to the position shown in Figs. 2, 3, 4 and 5, and the latch 89 is swung into engagement with the plates 88. The scoring mechanism 75 is now locked in position for the initial scoring. The die bar 79 is next swung upwardly and a strip of back material is inserted between the die bars 78 and 79 and beneath the pressure bar 32, lying over the paper already in the machine. The end of the back material is inserted a sufficient distance, so that its end will abut the forward edge of the gage 20, and when in this position the pressure bar 32 is lowered and bonds the material firmly in place. The die bar 79 is then brought forcibly down, for giving the initial scoring to the material. It might be noted at this point, that when the scoring mechanism 75 is in the locked position, the distance between the outer score line (indicated at A in Fig. 6) and the inner edge of the back material (indicated at B), is sufficient to completely receive the sheet of paper with a margin extending therbeyond, as clearly shown. The next scoring operation will be gaged by the thickness of the volume under construction.

The pressure bar 32 is now elevated and the latch 89 swung outwardly. The die bar 79 is elevated, and the cover material inserted under the pressure bar 32 until end B is even with the rear edge of the gage 20. The leaves to be bound are then placed evenly upon the back material so that their forward edges are even with the score line A, at which time the pressure bar 32 is lowered and firmly clamps the volume upon the table 18, with the free end of the back material extending between the scoring bars 78 and 79. The position of these scoring bars with respect to the carriage 15 is now determined by the position of the cam plate 49, it being remembered that this cam plate moves upwardly with the pressure bar 32. Thus, in the position illustrated in Fig. 6, the pressure bar 32 has been elevated in accordance with the thickness of the volume and, as shown, the cam plate 49 has been

elevated a corresponding distance, and has engaged and moved the scoring bar 79 outwardly to a position forwardly of the carriage 15 corresponding to the thickness of the volume under construction. The distance from the score line A to the score line C is equal to the thickness of the volume. The back is now scored a second time, and the material released from the scoring mechanism 75. The shaping bar 38 is now swung outwardly upon its pivot 38', and the back material is folded upwardly by the operator to the position illustrated in Fig. 6. The shaping bar 38 is then swung into normal position over the folded back portion and is locked in this position by the latch 41.

The back has now been formed, and the volume is ready to be drilled. The drill mechanism is moved along the rods 13 and 14 until the drill 70 is in position at a point beneath the volume. The operator then grasps the hand bar 59 and swings it forward, which movement lowers the carriage 15 and associated elements, this action resulting in the passage of the drill 70 through the notches 31, 36 and 40, and obviously through the volume. The operator may then place suitable binding fasteners through the openings, pressing them firmly into place by hand. The volume may then be released by the outward swinging of the shaping bar 38 and the subsequent elevating of the pressure bar 32. The volume may then be placed upon the table 18, with its bound head under the pressure bar 32. Lowering of the pressure bar 32 at this point will result in the binding elements being firmly forced into place. I contemplate employing fasteners of the type illustrated in Fig. 9, for which I have secured United States Letters Patent. Any projecting edges of the volume may be conveniently removed by the trimming mechanism shown.

It will be obvious from the foregoing that an extremely simple machine has been provided for carrying out the complete details involved in the binding operation. The device as a whole is compact, requiring a minimum of space in the shop, and is of such size to be portable if desired. The machine carries out each operation, from the gaging of the back material for the scoring, to the final drilling, binding and trimming.

It is to be understood that the invention is not limited to the precise construction set forth, but that it includes within its purview whatever changes fairly come within either the terms or the spirit of the appended claims.

Having thus described my invention, what I claim and desire to secure by Letters Patent of the United States is:

1. A book-binding machine of the character described, comprising a work table,

means associated with said table for retaining matter in position to be bound, and an adjustable scoring mechanism embodied in the machine and automatically set by the 5 positioning of the said retaining means and adapted to score material held upon the table and designed to form the back and covers for the volume under construction.

2. A machine of the character described, 10 comprising a binding table, compression means supported upon the table for retaining in place material to be bound, a scoring bar embodied in the machine and means for positioning the binding material with relation to the scoring bar whereby said scoring bar will score the back and cover material held on the table according to the thickness of the volume under construction.

3. In a book-binding machine, a work- 20 supporting table, means associated with the table for compressing matter to be bound, a movable scoring device, and means for moving said scoring device to position it to properly score material to be held on the 25 table so that said material will properly fit the volume under construction, to form back and covers therefor.

4. In a book-binding machine, the combination with a work-supporting table of a 30 compression means associated with said table, a scoring element movable toward and from said table, and a gage movable with the compression means and determining the position of the scoring mechanism.

5. In a book-binding machine, the combination with a work-supporting table of a 35 compression means associated therewith, a scoring device mounted for movement toward and from said work table, and means to determine the positioning of the scoring device, such means being positioned by the 40 positioning of the compression means.

6. In a book-binding machine, the combination with a work-supporting table of a 45 compression element associated with the work-supporting table, an adjustably movable die and die-bar to move toward and from the table, means controlled by the compression element to position the movable die and die-bar.

50 7. The combination with a work-supporting table, of a clamping bar, means for moving said bar vertically to clamp work upon the table, a shaper bar associated with the 55 clamping bar, and a scoring mechanism bodily movable toward and from the clamping bar, a gage movable with the clamping bar and means associated with the gage for positioning the scoring mechanism with respect to the clamping bar.

60 8. A machine of the character described for drilling books to be bound comprising a supporting frame, a work-supporting table mounted for vertical movement with respect 65 thereto, springs tending to resist the down-

ward movement of the work-supporting table, manually operable means for thrusting said table downwardly, a clamping means associated with the table, a scoring mechanism, and means associated with the 70 clamping means for positioning the scoring mechanism.

9. A machine of the character described for drilling books to be bound, comprising a supporting frame, a work-supporting table mounted for vertical movement with respect thereto, springs tending to resist the downward movement of the work-supporting table, manually operable means for thrusting said table downwardly, scoring mechanism 75 extending across the front of the table and bodily movable toward and from said table, and means for positioning the scoring mechanism in accordance with the thickness of the volume to be bound.

10. In a machine of the character described for drilling books to be bound, the combination with a work-supporting table, of a supporting frame upon which said table is mounted for bodily vertical movement, a gage, a clamping means by which the gage is carried, manually operable means for actuating said clamping means to compress the sheets of the volume to be bound, means tending to lift the table with respect to the frame, a past-center mechanism adapted to thrust said table downwardly or to hold it in elevated position after it is lifted, and a swinging scoring mechanism movable toward and from the table, its position being determined by the position of the clamping means.

11. In a machine of the character described for drilling books to be bound, the combination with a work-supporting table, of a supporting frame upon which said table is mounted for bodily vertical movement, a gage, a clamping means by which said gage is carried, manually operable members for actuating said clamping means to compress the sheets of the volume to be bound, means tending to lift the table with respect to the frame, a past-center mechanism adapted to thrust said table downwardly or to hold it in elevated position after it has been lifted, scoring mechanism mounted for bodily swinging movement toward and from said table, and a gage movable with the compression member for determining the positioning of the scoring mechanism with relation to the work table.

12. In a machine of the character described for drilling books to be bound in combination with a work-supporting table, a supporting frame upon which said table is mounted for bodily vertical movement, a gage, a clamping means by which said gage is carried, manually operable members for actuating said clamping means to compress the sheets of the volume to be bound, means

tending to lift the table with respect to the frame, and a past-center mechanism adapted to thrust said table downwardly or to hold it in elevated position after it is lifted.

- 5 13. The combination with a supporting frame, of a work table mounted for vertical movement thereon, a compression bar, power means for moving said bar vertically with respect to the table, manually operable 10 means for bodily moving the table to an upward or downward past-center position

when the table is elevated, a gage having an inclined outer face connected to the compression bar and movable vertically therewith, a scoring mechanism mounted for bodily swinging movement toward and from the work table and cooperating with said gage, a counterbalance for said scoring mechanism, and spring means tending to elevate said table. ¹⁵

ALEXANDER B. ROE.
